UNITED STATES PATENT OFFICE

2,421,125

LOW VOLTAGE HOT KNIFE

Paul Krebs, Detroit, Mich.

Application March 16, 1945, Serial No. 583,154

1 Claim. (Cl. 219—21)

1

This invention relates to hot knives adapted to be used for uncapping honeycombs. It may also be used in industries, wherein any heated knife may be employed such as in the butcher business, bakeries, for cutting tar, fatty solids, and the like.

An object of the invention is to provide a device of the character referred to, which employs a low voltage electric current so that any danger of shock or electrocution of the operator is eliminated.

Another object of the invention is the provision of a device of the character referred to, in which the cutting blade forms the heating element and vice versa.

Another object of the invention is the provision of a device of the character referred to, which is provided with novel means for cooling certain areas thereof, whereby the heat may be rapidly dissipated from the base of the blade so that the handle is prevented from getting unduly warm.

The foregoing and other objects and advantages of the invention will become more apparent as the description proceeds, reference being made from time to time to the accompanying drawings which form a part of the within disclosure, in which drawings:

Fig. 1 is a plan view of a device embodying my invention.

Fig. 2 is a side elevation of the device illustrated in Fig. 1.

Fig. 3 is an end view of the handle of the device illustrated in Fig. 1.

Fig. 4 is a schematic view of the electrical circuits.

Fig. 5 is a plan view of one of the radiators employed in dissipating the heat.

Referring now more particularly to the drawings, it will be understood that in the embodiment herein disclosed, my improved device consists of a cutting blade 7 which may be made of any suitable metal or alloy of metals to provide the electrical resistance required.

The blade 7 may be straight or tapered or may assume any desirable shape or size for the particular purpose for which it is adapted to be used. The blade 7 is provided with a central slot 8 which extends longitudinally throughout substantially the entire length of the blade and provides a suitable air gap between the two resulting sections of the blade.

The bifurcated portion of the blade 7 is mounted in suitable slots 9 formed in the handle 10, the latter being preferably made of non-heat conduct-

2

ing material. The blade 7 is secured to the handle 10 by rivets 11 or other suitable means.

A low voltage heat conductor is connected as at 12 and 13 to each respective section of the blade 7 so that a circuit is completed through the blade 7. The conductors 12 and 13 are connected to flexible conductors 14 and 15 which are in turn connected as at 18 and 19 to the secondary winding 20 of a suitable transformer 21, the primary winding 22 of which is connected to high voltage lines 23 and 24, in the circuit of which is positioned a multi-post switch 25, whereby various loads may be introduced to the primary winding 22.

15 26 indicates a pilot light positioned in the secondary circuit which indicates when the device is in operation.

In order to help cool the handle 10 and maintain a comfortable temperature therein for the operator, I employ a radiator element 27 on each section of the blade 7. The radiators 27 are channel-shaped copper members which are riveted as at 28 to the respective sections of the blade 7. Holes 29 may also be positioned in the blade 7 25 adjacent to the handle 10 to reduce the stock and provide air spaces for further dissipation of the heat in this area.

When the knife is electrically connected to the secondary winding 20 of the transformer 21, a 30 low voltage current, approximately $1\frac{1}{3}$ volts, is permitted to flow through the leads 14 and 15, completing a circuit through the two sections comprising the cutting blade 7. When the knife is cooled, the circuit will draw approximately 136 amperes which will heat the knife to a temperature of approximately 212° Fahrenheit more or less. As the temperature of the knife blade increases, the amperage will be reduced until it reaches the point of approximately 89 amperes 40 when the blade reaches its highest temperature. The temperatures and amperage herein stated, of course, will vary in different size blades and with different materials used.

The blade will start to heat first at the point 45 around which area the highest degree of temperature will be maintained during the heating operation.

The section of the blade adjacent to the handle will normally operate at a slightly lower temperature.

Inasmuch as we are utilizing only approximately $1\frac{1}{3}$ volts, the blade may be plunged into water or may be grasped by the hand or may be short-circuited otherwise without danger of 50 shocking the operator or destroying the device.

Having described my invention, what I claim and desire to secure by Letters Patent is:

In a device of the character described including a bifurcated blade and a handle, an offset portion in said blade adjacent the handle, low voltage leads connected to the respective legs of said blade at said offset, and a channel member of great heat conductivity across said blade beneath said offset and adjacent said handle.
